UNITED STATES PATENT OFFICE

WILLIAM L. HALLETT, OF ARLINGTON, MASSACHUSETTS

WATER HEATER

Application filed October 20, 1927. Serial No. 227,476.

This invention relates to automatic storage gas systems for supplying hot water for domestic purposes, and has particular reference to means for maintaining efficiency and cleanliness in the boiler and for enabling a mixture of hot and cold water to be readily obtained when desired. Heretofore in heaters of this character, so far as I am aware, the gradual accumulation of rust and sediment in the boiler blankets the heating surface at the bottom of the boiler. Also in prior structures the escape of the heating gases is so rapid as to lose a great deal of its efficiency.

I overcome these objections by a structure of the bottom portion of the boiler and connections for effecting automatic flushing. I overcome the latter objection by providing a structure which traps a large proportion of the heating gases in a space surrounding the upper portion of the boiler whereby the temperature of the water in the boiler is not reduced by radiation of heat therefrom into a space from which the gases can escape.

With the above mentioned objects in view my invention consists in the construction and combination of parts substantially as herein-after described and claimed.

Of the accompanying drawings:—

Figure 1 is a sectional elevation of my improved water heater in one of its forms.

Figure 2 is a partial sectional view of the same taken in a vertical plane through the flue for gases.

Figure 3 represents a section on line 3—3 of Fig. 2.

Similar reference characters indicate similar parts in all of the views.

The outer shell 12 and inner shell 13 of the casing of the heater, of any suitable metal, and with suitable insulating material 14 between them, and supported by legs 15, may be of any preferred shape and dimensions.

The boiler or water chamber is spaced from the inner shell of the casing and comprises a wall 16 with a suitable top member, said boiler being supported by lugs 17. The bottom of the boiler is indicated at 18.

Secured in the bottom of the boiler is a chamber the top of which is indicated at 19,

a wall 20 and bottom 21, said chamber being of non-corrodible metal such as copper.

Leading from the top of the inner chamber 19, 20 and 21 is a short pipe 22 having a cowl 23 at its top supported by strips 24. Also rising from the top of said inner chamber is a pipe 25 preferably leading nearly to the top of the boiler.

The inner shell 13 of the casing has a hole 26 which communicates with a flue 27 between the inner and outer shells of the casing, the insulating material being, of course, omitted in a narrow vertical space to provide for said flue. The upper end of the flue 27 communicates by means of a flue 28 in the top of the casing with the usual outlet 29.

A suitable gas burner of any well known or preferred structure is indicated at 30 being supplied by a gas pipe 31 to which is connected a pilot burner 32. As the gas burner 30 may be of any well known structure it is unnecessary to illustrate details thereof. The supply of gas, coming through a pipe 33 is controlled by any one of the well known thermostatic devices indicated as a whole at 34, the details of which do not require illustration. The usual tube projecting into the body of water in the boiler and containing part of the thermostatic mechanism is indicated at 35.

The outlet pipe for hot water from the top of the boiler is indicated at 36 and the supply pipe for cold water is indicated at 37, the latter communicating by an elbow with a short pipe 38 through the heater casing and through the wall 20 of the inner chamber and close to the bottom wall 21.

Diametrically opposite the pipe 38 a pipe 39 extends out from the inner chamber and is provided with a suitable valve for controlling escape of water through a suitable outlet 40 for use when the boiler is to be drained.

Connecting the hot water pipe 36 and the cold water pipe 37 is a pipe 41 having a thermostatically controllable valve 42, the ends of the pipe 41 extending into small chambers or couplings in the pipes 36—37 and having upwardly turned nozzles or nipples 43.

In operation the hot gases contact, of course, with the bottom of the boiler and pass

up around the space between the inner wall 13 of the casing and the wall 16 of the boiler but are not allowed to escape freely from the top of said space. That which must escape 5 passes through the hole 26 and the flues 27—28, but the hottest portions of the products of combustion remain trapped in the upper portion of the space above the hole 26 and such trapped products of combustion are constantly 10 replenished and kept hot by the gases rising from the heater. An important advantage in this structure is that when the gas burner 30 is not in operation, the gas having been shut off after any length of burning, the hot 15 gases or products of combustion remaining trapped in the upper part of the space around the boiler prevents radiation of heat from the boiler and consequently retains the water in the boiler at a higher temperature than 20 would be the case if the said products of combustion or hot gases were free to escape. During operation the chief absorption of heat by the water occurs, of course, in the inner chamber at the bottom of the boiler and the hot water therefrom rises through the pipe 25 and if not being drawn off returns by the natural process of circulation under the cowl 23 and through the pipe 22 back into said inner chamber. If the water contains any 25 sediment or other objectionable matter such sediment or matter is deflected by the cowl 28 to the outside of the pipe 22 and is deposited on the top 19 of the inner chamber.

Of course, the supply of cold water, when 30 needed, enters through the pipe 38. When, however, it is desired to remove any sediment or other substance from the bottom of the inner chamber, the valve of pipe 39 is opened so that cold water can flush the bottom of said 35 inner chamber. Of course, the flushing operation just described is more effective if the boiler is first practically emptied by means of the outlet pipe 39. Whenever hot water is drawn from the boiler the inflow of cold water tends 40 to sweep any deposit of sediment which is on the bottom 21 of the inner copper chamber such substances being carried along by the water, or some of the substances, up through the pipe 22, the result being that 45 the bottom of the inner chamber, and in fact the bottom of the boiler where the heat from the burning gas is most intense is kept practically clean.

The object of the by-pass structure including 50 a pipe 41 and its nipples 43, or any equivalent thereof such as hereinafter mentioned, is to provide for a mixture of cold water from the pipe 37 with the hot water passing from the boiler through the pipe 36. With the structure illustrated, it is obvious that when the valve 42 is opened more or less, and hot water is being drawn through the pipe 36, there will be a natural tendency for some 55 cold water to pass through the pipe 41 and

mix with the hot water being drawn through pipe 36.

I do not limit myself to the particular construction including the valved pipe 41 having the nipples 43 for effecting the temperature regulation described as other, such as manually operated devices, may be employed for controlling the passage of water through the pipe 41.

The by-pass construction is for the purpose of gaining additional volume of hot water at the faucet without the use of the larger boiler and the entire heater construction. The boiler will be made to carry a very high temperature of water which when reduced at the by-pass will result in a larger volume for use at the faucet.

Having now described my invention, I claim:—

1. The combination with a water heater 55 boiler, of an inner chamber at the bottom of said boiler, a connection for cold water to said chamber, a pipe leading from said chamber to the upper portion of the boiler, and a cowl-protected opening in the top of said chamber.

2. The combination with a water heater 60 boiler, of an inner chamber at the bottom of said boiler, a connection for cold water to said chamber, a pipe leading from said chamber to the upper portion of the boiler, a cowl-protected opening in the top of said chamber, and a valve-controlled outlet from said chamber opposite the said connection for cold water.

3. The combination with a water heater 65 boiler having hot and cold water pipes connected thereto, of a by-pass connection between said pipes, said by-pass having a nipple at each end, said nipples facing in directions to take water from the cold water pipe and deliver it to the hot water pipe.

4. An automatic storage water heater having 70 its boiler provided with a partition at its lower end forming with the bottom of the boiler an internal chamber, said partition being provided with passageways for permitting circulation of water through said chamber, connections being provided for flushing said chamber, the said connections for flushing including a cold water supply pipe so positioned that the discharge therefrom will sweep across the bottom of said chamber.

5. The combination with a water heater 75 boiler having hot and cold water pipes connected thereto, of a by-pass connection between said pipes, said by-pass having a nipple at each end, said nipples facing in directions to take water from the cold water pipe and deliver it to the hot water pipe, thermostatic means being provided for controlling said by-pass connection.

In testimony whereof I have affixed my signature.

WILLIAM L. HALLETT.
